UNITED STATES PATENT OFFICE.

GIOVANNI LOMBARDO, OF WHITE PLAINS, NEW YORK.

PAPER-DISPENSING APPARATUS.

1,196,372.

Specification of Letters Patent. Patented Aug. 29, 1916.

Application filed September 18, 1915. Serial No. 51,336.

To all whom it may concern:

Be it known that I, GIOVANNI LOMBARDO, a citizen of the United States, and a resident of White Plains, in the county of West-
5 chester and State of New York, have invented certain new and useful Improvements in Paper-Dispensing Apparatus, of which the following is a specification.

This invention relates to improvements in
10 paper dispensing apparatus, particularly as used in conjunction with barbers', dental, surgical and other reclining chairs, to furnish sanitary coverings for the head rest and at the same time, sheets of paper for
15 wiping off razors, instruments, etc. Its principal objects are: First, to provide a covering inexpensive in cost, that can be easily and quickly renewed so that occupants of the chair may each be provided
20 with a fresh, unused and hence clean and sanitary cover upon which the head rests, the waste paper serving at the same time for use in cleaning instruments, and secondly, to provide means whereby the material used
25 as coverings may be supplied in sheet form from a roll, and the roll itself renewed from a supply source without dismounting from its supports. These and other objects are attained by the novel construction and
30 combination of parts hereafter described and shown in the annexed drawing, which form a material part of this specification, it being understood that changes may be made therein without departing from the
35 scope of the claims hereto appended.

Referring to the drawings: Figure 1 is a perspective view showing the upper part of a chair having a head-rest with the attachment applied and indicating in broken lines
40 the arrangement for replenishing the sheet supply roller. Fig. 2 is a vertical sectional view of the same. Fig. 3 is a partial elevational, partial sectional view of the supply roller and casing. Fig. 4 is a transverse
45 sectional view, taken on line 4-4 of Fig. 3, drawn to an enlarged scale. Fig. 5 is a fractional view showing a modification of the roller and casing shown in Fig. 3. Fig. 6 is an elevational view in detail of the roller. Fig. 7 is an enlarged sectional view, taken on line 7-7 of Fig. 6. Fig. 8 is a fragmentary perspective view of the feed roller support, and Fig. 9 is a perspective detail view of one of the paper supply sup-
55 ports.

In these drawings the chair, referred to

by the numeral 15, has attached to it a head-rest 16, by means of the sliding bar 17, which may be adjusted as to height or removed in the usual manner; an adjustable 60 pivoted joint 18 is commonly provided so that the head-rest can be set and clamped at any preferred angle, the rest being further provided with a cushion 19 for the comfort of the occupant of the chair. 65

Rigidly attached to the ends of the side elements 20 of the head-rest, near the joint 18, is a cylindrical casing 21, having permanently formed ends or heads 22 provided with hubs 23; part of the casing 21 is 70 formed by a cover 24, hinged at 25 and secured in position, when closed, by catches 26, thus permitting access to the interior of the cylinder.

The edge of the cover 24 does not extend 75 quite to the corresponding edge of the fixed portion of the casing but presents an open slot 27 through which paper wound upon the roller 30 may extend. This roller 30 is also slotted, as at 31, to receive the end of 80 the paper sheet 28 so that it may be wound upon it or dispensed. A fixed collar 32 at one end and the hub of the gear 33 fastened upon the roller at the other prevent longitudinal movement of the roller. 85

Near the rear ends of the bars 20 are formed two circular apertures 35 and 36 opening into each other and adapted to receive the ends of the feed rolls 37 and 38, over the first of which the paper sheet 28 90 passes and then under the other over the block 39 and below the knife 40, fixed to extend between the bars 20, and adapted to sever the sheet when the extending end is raised forcibly against its cutting edge. 95

A crank handle 42 is secured to the extending end of the feed roll 37 by which it may be turned, thus frictionally engaging the paper sheet and advance it outward to such an extent as may be desired. On the opposite end of the roll 37 is secured a gear 43 in operative relation to the gear 33, a chain 44 being used to communicate motion therebetween when it is desired to replenish the supply of paper upon the roller 30, and it 105 is to be noted that the chain 44 is sufficiently loose or slack to allow it to be entirely removed when not in actual use.

Upon the bars 20 are rigid sockets 46, in which may be removably affixed the lower 110 ends of supports 47, the forked ends 48 of which are adapted to receive the shaft 49 of

the paper supply roll 50, which may be temporarily mounted thereon while supplying the roller 30 with such quantity of paper as the casing 21 may hold.

5 In the modified form of casing shown in Fig. 5 a tube 52 is provided with a slot 53 and furnished with removable ends 54 held in engagement by the creases 55 which allow the end covers to be snapped into place; in 10 other respects the construction is as before described.

In operation, the supports 47 are inserted in the sockets 46, the supply roll mounted on them, the free end of the sheet being passed 15 into the casing through the slot 27 and engaged with the slotted roller 30, and the chain 44 being on the gears, the handle 42 is turned, causing paper to be wound upon the roller 30 until a sufficient quantity has 20 been received. The paper is then severed in any convenient manner, the end being brought over the cushion 19 and fed between the feed rollers 37—38, turned by the handle 42. The main supply roll 50, its supports 25 and chain are then removed and the device is ready to be used in an obvious manner. It is to be noticed that the paper will be tightly stretched and lie smoothly over the surface of the cushion and that upon operating the handle, it will be drawn outwardly to a point where it can be grasped and severed by the knife 40, so that no waste need occur. Thus it is possible to use a relatively small 30 supply roll, unobjectionable in appearance, nowise in the way or causing discomfort to the occupant of the chair.

It will be obvious that from a sanitary standpoint the advantages are superior as only the sheet in use comes in contact with 40 the person, the remainder of the paper being protected from perspiration, handling, dirt, etc. and that the use of the device is far more economical than by paper in the form of a pad; also that the used sheets 45 can be made further use of in wiping instruments as razors and the like, effecting a very material saving.

Having thus described my invention and ascertained the manner of its construction 50 and use, what I claim as new and desire to secure by Letters Patent, is:—

1. A head-rest cover attachment comprising a pair of support bars, a slotted cylindrical casing rigidly carried by said bars, 55 a paper receiving roller revolvably mounted in said casing, paper feed rollers mounted in said bars at the opposite ends thereof, a knife adjacently parallel to said feed rollers, means for rotating said feed rollers and 60 means for supplying paper without dismounting said receiving roller.

2. A head-rest cover attachment comprising a pair of bars, a fixed cylindrical casing at one end of said bars, a paper carrying 65 roller revolvble therein, a pair of feed roll-

ers mounted in peripheral contact at the opposite ends of said bars, means for rotating one of said feed rollers, means for communicating rotary motion between said feed rollers and said carrying roller, an auxiliary 70 paper supply source removably engageable with said bars and means combined with said casing whereby access may be had to said carrying roll in securing paper thereto.

3. A head-rest cover attachment comprising 75 a cylindrical casing having a fixed part and a movable part hinged longitudinally thereto, a slotted roller revolvble in said casing adapted to engage the end of a paper sheet, a supply source for paper, said supply source being removably engaged with the attachment, means for winding paper from said supply source upon said slotted roller and means for dispensing the paper 80 from said roller.

4. In combination with a substantially rectangular head-rest, of a pair of bars secured laterally thereof, a slotted casing fixed at one end of said bars, a roller adapted to receive or dispense paper revolvably mounted centrally of said casing, feed rollers at the opposite ends of said bars, a knife parallel thereto, means for rotating said feed rollers and a driving means between said rollers and said paper roll whereby it may 95 be rotated in either direction.

5. In combination with a cushioned head-rest, of a frame attached at the sides thereof, a cylindrical casing rigidly mounted on one end of said frame, a paper engaging roller revolvble in said casing, said roller being accessible through the walls of said casing, sockets on said frame, supports removably engageable in said sockets, a paper supply roll carried by said supports, the paper thereon being engageable with said roller, feeding means mounted in said frame at the opposite end thereof, means for cutting the paper into sheets, adjacent to said feeding means, means for winding paper from said supply roll upon said roller and means for advancing the sheet from said roller.

6. The combination, with a chair and a head rest mounted thereupon, of a substantially cylindrical casing disposed adjacent one edge of said head rest and provided with a slot, a paper holding roller revolvably mounted within said casing, paper feed rollers disposed adjacent the edge of said head rest opposite said casing and in suitable position to draw paper from said first mentioned roller and across said head rest, and gearing connecting said first mentioned roller with said paper feed rollers in order 115 to enable said paper holding roller to be driven positively by movements of said paper feed rollers, independently of the tension of the paper.

7. The combination, with a chair and a 130

head rest mounted thereupon, of a casing disposed adjacent one edge of said head rest, a paper-dispensing roller located within said casing, paper feed mechanism disposed adjacent the edge of said head rest opposite said casing for the purpose of drawing paper from said paper dispensing roller and across said head rest, a sprocket wheel carried by said paper feed mechanism, another sprocket wheel carried by said paper dispensing roller, and a sprocket chain connecting said sprocket wheels for enabling said paper dispensing roll to be driven by movements of said paper feed mechanism, independently of the tension of the paper. 10 15

In testimony whereof I have signed my name to this specification.

GIOVANNI LOMBARDO.
